VALVE DEVICE

Fred A. Kommer, St. Louis, Mo.

Original application November 27, 1934, Serial No. 754,940. Divided and this application February 24, 1936, Serial No. 65,267

6 Claims. (Cl. 277—45)

This invention relates to valve devices, particularly of the type used in fluid pressure systems to control the pressure therein. The invention is of particular advantage when used in connection with internal combustion engine carburetors having pressure accelerating devices as more fully described in a copending application Serial No. 754,940, filed November 27, 1934, of which the present application is a division.

10 In the design of present day carburetors of the above character wherein an accelerating pump of the pressure injection type is connected to a throttle valve, it becomes necessary to vary the quantity of fuel discharged by the pump to meet the requirements of various throttle opening movements. It will be seen that, upon a sudden opening of the throttle valve to a full open position, the vacuum in the intake manifold will drop very low, and a full capacity discharge from an accelerating pump which has been designed to meet requirements for rapid part throttle acceleration, would be excessive at this time, particularly since, as is usually the case, additional fuel is also admitted through the main fuel supply system when the throttle is fully open.

15 An object of the invention is to provide a device of the above type having a part functioning under certain conditions as a check valve for permitting fluid to pass therethrough in one direction only and also functioning to by-pass fluid around said check valve part under certain conditions.

Another object is to provide valve means of the above type capable of insertion in a chamber to limit the rate of flow of fuel therethrough in a given direction.

Another object is to provide a relief valve device which may be utilized with particular advantage in connection with carburetor accelerating pump.

Another object is to provide a compact, simple, rugged, combination check and relief valve device which may be conveniently applied, removed, and handled as a unit.

45 Other objects and advantages will appear from the following description and accompanying drawing, referring to which

Figure 1 is a diagrammatic representation of a carburetor embodying my invention.

50 Figure 2 is an enlarged sectional view showing the by-pass relief valve and portions of communicating passages.

55 Figure 3 is a side elevation of the relief valve inner cylinder.

Figure 4 is a plan view of the inner cylinder shown in Figure 3.

Figure 5 is a side elevation of the relief valve cage.

Figure 6 is a bottom plan view of the relief 5 valve cage shown in Figure 5.

Figure 7 is a side view of the by-pass relief valve unit.

Referring to the drawing, showing the invention applied to an internal combustion engine 10 carburetor, reference numeral 1 indicates the main body of a carburetor, having an air inlet 2 venturis 3, 4, and 5, a mixing chamber 6, and an outlet 7. The admission of air to the carburetor is controlled by the choke valve 8 carried 15 by a pivotal shaft 9 and operated either manually or automatically. The carburetor is supplied with fuel through the intake 10, and the fuel level, substantially as indicated, is maintained in the constant level chamber 11 by conventional 20 means usually including a float 12 and needle valve 13. Fuel is supplied to the primary venturi 3 through the main discharge nozzle 14 and the supply may be varied by a metering rod 15 which may be actuated by an interconnection to the 25 throttle or by vacuum or by any other suitable means.

20 A conventional adjustable idle device composed of passages 16 and 17 leading to the idle port or ports 18 and having an adjustment screw 19 is 30 provided for low speed operation. A throttle valve 20 is mounted for rotation with shaft 21 and may be operated in any manner through lever 22 which is affixed to the shaft. In order to supply additional fuel for acceleration an accelerating pump 35 is provided comprising a cylinder 23 and a piston 24 arranged to reciprocate in the cylinder and attached to piston rod 25. The accelerating pump shown in the drawing is operatively connected to the throttle valve through links 26 and 27 and levers 22 and 28. It may, however, be operated by vacuum and spring means and it will be understood that the details of the accelerating pump and means for operating same do not constitute the present invention.

40 Fuel is drawn into the accelerating cylinder from the float chamber through passages 29 and 30 and through orifice 31, passing the intake ball check 32 as the same is lifted from its seat by the upward surge of fuel as piston 24 moves upward. 50 The effect of restriction 31 in limiting the inflow of fuel is to insure the formation of an air space between the top of the fuel and the piston, whereby an air-cushioned discharge is obtained. Preferably the capacity of the fuel pump is substan- 55

tially greater than the maximum required discharge. Fuel is discharged into the mixing conduit through passages 33 and 34, passing discharge ball check 51, and through discharge jet 5 36 and restriction 50.

The novel combination check and relief valve device comprises a sleeve or main body member 37 externally threaded for engagement with the carburetor body, and a ball cage member 40 slidably received within the bore or chamber in sleeve 37. The sleeve includes a shouldered portion 42 between the lower and upper portions 38 and 39 thereof, a collar 37A for limiting the extent to which the sleeve may be screwed into the threaded aperture therefor in the carburetor body, and restricted inwardly bent tongues 46 forming a screw driver slot 47 for assembly of the sleeve with the carburetor, the bent tongues also forming a seat for the coil spring 43. Spring 43 at its upper end engages the cage member 40 for urging the same upwardly with its annular shoulder 41 normally in engagement with the shouldered portion 42 of the outer sleeve. Check ball 32 is loosely held within the hollow upper portion of the cage member by lip elements 45 bent inwardly to maintain the assembly. Ball 32 is urged by gravity against the upper end of restricted orifice 31 in the ball cage member and functions to prevent fluid from passing downwardly through this orifice while permitting fluid to be drawn into the pump cylinder during upward movement of the piston.

In case sufficient pressure in a downward direction is applied to the cage member 40, due, for instance, to rapid depression of the pump piston, the member 49 will be moved downwardly against spring 43, separating shoulders 41 and 42 on the cage and sleeve members 40 and 37, respectively, and permitting a portion of the fluid to by-pass 40 between the loosely fitting walls of the cage and sleeve members and through the passages 30 and 29 back into the constant level chamber. Thus, the valve structure functions under certain pressure conditions as an ordinary check valve and under different pressure conditions as a by-pass 45 so as to substantially limit the pressure which can be applied to fuel in the pump cylinder and consequently the rate of discharge of accelerating fuel through the restriction 50 in auxiliary nozzle 36.

The novel valve structure may be advantageously used, as illustrated, in connection with an internal combustion engine carburetor having an accelerating pump actuated, for instance, by opening of the throttle. When the throttle is suddenly opened and the engine is operating at relatively low speed, the suction within the carburetor ordinarily will be reduced substantially to a point where the gasoline supply, augmented by the action of the accelerating pump and, as is frequently the case, by the admission of additional fuel directly into the main fuel supply system, cannot be properly atomized, mixed with air, and carried to the firing chambers. In case 55 the throttle is only partly opened, or is opened slowly, so as to create insufficient pressure in the pump cylinder to open the relief valve, the suc-

tion and velocity in the carburetor will ordinarily be sufficient to care for the additional fuel.

The novel valve structure, while particularly advantageous when applied to an internal combustion engine carburetor, as described, is obviously not limited to such use, but may be conveniently and advantageously used in substantially any pressure fluid system in which it is desirable to limit the fluid pressure in a passage or chamber and to combine check and relief valves in a unitary, compact, simple and durable structure. The device may be conveniently applied and withdrawn as a unit and the parts thereof are maintained firmly assembled at all times due to the novel construction. 15

Various details of the invention as shown and described are not essential and these, together with the particular application or use of the novel valve structure, may be varied, as will occur to those skilled in the art, and the exclusive use 20 of all such modifications as come within the scope of the appended claims is contemplated.

I claim:

1. A valve device comprising a body member having a bore and threads, said member having 25 restricted offset portions for receiving a tool to facilitate assembling the device with associated structure, said offset portions also forming valve structure abutments, and a valve in said body member and operatively associated with said 30 abutments.

2. A device as specified in claim 1 in which said offset portions are in the form of tongues bent inwardly from the wall of said body member adjacent an end thereof. 35

3. A valve unit comprising a body member in the form of a sleeve having an internal shoulder and restricted tongue elements bent inwardly adjacent an end thereof, said elements forming recesses for cooperating with a tool for assembling 40 the unit with associated structure, a member loosely fitted in said body member and having a chamber therein and a metering orifice communicating with said chamber, a spring compressed between said tongue elements and said loosely 45 fitted member and normally holding the same against said shoulder to seal the space between said members, and a check valve in the chambered portion of said second member and controlling said metering orifice, said chambered 50 member being adapted to be moved against the force of said spring to open a passage between said members.

4. A valve device comprising a hollow body member having an internal valve seat forming 55 shoulder and restricted, laterally bent portions at one end for cooperation with a tool in attaching the device to associated structure, a valve in said body member, and a spring compressed between said valve and said bent portions for 60 urging said valve toward said internal shoulder.

5. A device as specified in claim 4 in which said valve includes a passageway and carries a second valve for controlling said passageway.

6. A device as specified in claim 4 in which said 65 bent portions form a screw driver slot.

FRED A. KOMMER.
